INVENTOR:

FREDERICK B. ADAM.

By Elera & Schawmberg,
ATTORNEYS

UNITED STATES PATENT OFFICE

FREDERICK B. ADAM, OF ST. LOUIS, MISSOURI

PANELBOARD MOUNTING MEANS

Original application filed December 26, 1925, Serial No. 77,682. Divided and this application filed December 23, 1927. Serial No. 242,214.

This invention relates to improvements in panelboard mounting means and more particularly to an adjustable means for mounting electric panelboards inside of enclosing cabinets.

This invention is a division of the subject matter originally included in my co-pending application, Serial No. 77,682, filed December 26, 1925.

An object of this invention is to provide a means for mounting a panelboard inside an enclosing cabinet at a given distance from the door or front portion thereof, regardless of the absolute depth of the cabinet.

A further object is to provide a means for adjustably securing a panelboard inside a cabinet in such a manner that the panelboard may be adjusted, both distantly and angularly with respect to the cabinet.

A further object is the provision of a mounting back for a plurality of panelboard units, and which may be adjusted to compensate for units of different depth.

Further objects and advantages of this invention will appear from the drawings and the following detailed description.

My invention consists in the novel construction, arrangement and combination of parts as hereinafter fully and clearly described, definitely pointed out in my claims and illustrated in the drawings, in which:

Fig. 1 is a fragmentary perspective view, partly in section, of a cabinet and panelboard constructed in accordance with my invention; Fig. 2 is a fragmentary plan view of a strip which forms a portion of the mounting back for the panelboard; and Fig. 3 is an enlarged detailed sectional view showing the adjustable connection between the mounting back and the cabinet back.

Referring by numerals to the drawings, 15 designates the back, 16 the top, and 18 the sides of the cabinet or box. I prefer to provide an inturned flange 20, surrounding the cabinet at the margins of the top, bottom and sides, all of which may be formed as a unit of sheet metal. For economy of space in shipping and handling, and for ease of assembly, I prefer to provide a trim 21, of open-frame construction and a closure or door 22,

arranged in the open frame. By preference, trim and door are detachably secured to the cabinet by some suitable clamping means, such as is shown at 23.

Next to the trim, on the inside thereof, and preferably affixed thereto as by welding, is an open frame comprising a flat portion 24. This flat portion extends a short distance into the door opening of the trim to provide a stop 25, for the door in its closed position. The frame is continued, rearwardly, by the inclined return 26, and the return terminates in a rearwardly extended flange 27. The advantage and novelty of the construction of the trim, door, and connected portions are made the subject of a separate application and the details and novelties thereof depicted in detail in my co-pending application, filed December 23, 1927, Serial No. 214,211. By preference, the flange 27 will contact with the panelboard, which may, or may not, be composed of sectional units, but which is formed of insulating material. A portion of the panelboard, or one section thereof, is indicated at 36. By preference the cabinet and apparatus inside thereof are so disposed that the flange 27 contacts with the panel section 36.

As a means for effecting a distance adjustment between the panelboard and the flange 27, I prefer to employ spacer nuts 30, and studs 28, for location between the back 15, of the cabinet and the mounting back 29 for the panel. The spacer nuts 30, are carried by the studs 28, between the strip 29 and the cabinet back. The strips 29, are provided with holes 31, the diameter of which is somewhat in excess of the diameter of studs 28, which permits the mounting back 29, carrying the panelboard, to be adjusted angularly 90 inside the cabinet. Holes 31 are, by preference, circular in form but may be of other suitable shape. The distance adjustment of the panel is effected by the location of the spacer nuts 30, on the studs 28. When the mounting back, with or without the panels, is once positioned in a particular cabinet, this position is maintained by means of the retaining nuts 32, on the studs 28, and in front of the strips 29. When the strips 29, 100

are of substantial length, flanges 33, are preferably provided, as stiffening elements. The flange 33, may consist of an integral portion of the strip 29, turned inwardly at a right angle thereto. As a retaining means for the panelboard, or units thereof, I prefer to provide on the mounting strips 29, a series of screw seats 34, which are spaced a uniform distance from the edge of the strips 29, and serve to receive screws 35, for positioning the panelboard or the several units thereof.

The advantages in practical use and installation of my device will be apparent, to those skilled in the art, from the above description of parts. It will be seen that the arrangement as a whole provides a means for mounting the panel, or panelboard, inside an enclosing cabinet so as to permit its ready insertion or removal without any disturbance of wall structure about the cabinet. The advantages of the use of a pair of separate strips 29, composing a mounting back for the panelboard or its sections, will be at once apparent. These strips may be stacked and nested for shipment and handling and the use of separate mounting back elements permits greater nicety and ease of adjustment than does the usual one piece mounting back.

In case it becomes necessary to plumb or adjust the mounting back vertically, the spacer nuts 30, the holes 31, and retaining nuts 32 render it a simple matter for one man to adjust the entire panel relative to the cabinet. By means of such an adjustment the necessity of exact location of screw holes in the mounting back and cabinet back is eliminated.

The described adjustable feature of the strips composing the mounting back for the panel is adapted to be used in an arrangement such as is illustrated in Fig. 1, in which the panel units are notched as at 48 to receive the flanges 27 of the return. This arrangement holds the return at a suitable insulating space from live panelboard parts and serves to align the panel with the cabinet front. As a consequence, when the panel board is aligned and plumbed, the mounting strips 29, and the front of the cabinet which comprises the trim 21, and door 22, are plumb at the same time. The adjustment of the spacer nuts 30, and the retaining nuts 32, permits forward movement of the panelboard to meet the flange 27, of the return, regardless of the distance separating the trim and the cabinet flange.

What I claim is:

1. A panelboard, a cabinet, and a panel mounting comprising a strip adapted for securing to the panelboard, and having a bolt opening adjacent each its ends, bolts carried by spaced portions of the cabinet, and being of lesser diameter than said openings,

and a plurality of holding means threadedly associated with each of said bolts, and arranged for engagement with opposite sides of the strip adjacent the associated bolt opening.

2. A panelboard, a cabinet, and a panel mounting comprising a metal strip extending transversely of and beyond the panelboard, and having a series of aligned seats for receiving panel screws, an oversize bolt opening adjacent each its ends, bolts extending through said openings into a wall of the cabinet, and holding means adjustably engaging each bolt and the adjacent opposite sides of said strip, and adapted for positioning the strip in adjusted relation with respect to the cabinet.

3. In combination with a panelboard and a cabinet therefor, a mounting device for the panelboard comprising a metal strip, having a trend along the back of the panelboard and projecting substantially beyond the panelboard, and positioning means in connection with said strip adapted to provide for adjustments of said panelboard and strip with respect to the cabinet, said means including a threaded member extending through the projecting part of the strip and into a wall of the cabinet and a portion of the strip having an oversize aperture for receiving the threaded member.

4. A mounting means adapted for the support of a panelboard assembly within a cabinet, said means comprising a metal plate adapted for securing to the panelboard, and extending along one wall of the cabinet, means rendering said plate spacially adjustable with respect to said wall of said cabinet, and a plurality of holding means extending through said plate and into the cabinet wall, said holding means and plate being related to permit angular adjustment of said plate with respect to said cabinet.

5. A means for mounting a panelboard in a cabinet, comprising a stud projecting from a wall of said cabinet, an adjustable spacing means on said stud, a plate adapted for the support of the panel, said plate having an opening therein of substantially greater size than necessary to receive said stud, said opening, spacing means and stud being adapted to permit angular adjustment and distance of the plate and panel with respect to the cabinet, and a retaining means on said stud.

6. A device for mounting a panelboard assembly in a cabinet, comprising stud bolts projecting inside the cabinet, spacing nuts and retaining-nuts on said stud bolts, a panelboard carrying member having apertures therethrough substantially greater in size than the diameter of the stud bolts, whereby said member may be angularly and distantly adjusted with respect to a wall of said cabinet.

7. A panelboard, a cabinet and a panelboard mounting comprising a metal panel-

carrying member of strip form, stud bolts projecting inside the cabinet, spacing nuts and retaining nuts on said stud bolts, said metal strip being provided with screw seats,
5 having apertures therethrough substantially greater in size than the diameter of the stud bolts, whereby said strip is angularly and distantly adjustable with respect to a wall of the cabinet, and holding elements engaging
10 said panelboard and resident in the screw seats on said strip.

8. A device for mounting a panelboard in a cabinet, comprising stud bolts projecting inside the cabinet, spacing nuts and retaining
15 nuts on said stud bolts and a panelboard carrying member having apertures therethrough adapted to receive said stud bolts, and to permit free adjusting movement of the bolts in any direction within the openings, whereby
20 said member may be adjusted, universally, with respect to a wall of said cabinet.

9. A sectional panelboard, a cabinet, a mounting metal back for securing the sections of said panelboard in assembled relation,
25 said mounting back comprising a pair of members, each having aligned screw seats for the reception of holding means for said sections, and an opening adjacent each of its ends, bolts projecting into said cabinet
30 and said openings, and having a substantially lesser diameter than the diameter of the openings, and a pair of nuts on each of said bolts, arranged for engagement with opposite sides of the mounting back, adjacent the corresponding bolt opening.

10. A panelboard assembly including a panel portion of insulating material, a cabinet for the panel portion, mounting members formed of metal strip material and extending from opposite sides of the panel portion, screws extending from the panel portion into the mounting members, each of said members having a seat for one of said screws, additional screws extending through said
45 mounting members and into wall portions of the cabinet at points beyond the panel portion, said members having openings for said last-named screws, the openings being of substantially greater area than necessary to
50 accommodate their screws, whereby to permit relative adjusting movement of said mounting members with respect to the cabinet.

FREDERICK B. ADAM.
